CLAIM

The ornamental design for a clamp, as shown and described.

DESCRIPTION

FIG. 1 is a front, top, and right side perspective view of the clamp, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear, top, and right side perspective view of the clamp attached to a medical pump.
The features shown in broken lines depict environmental structure only and form no part of the claimed design.**1 Claim, 8 Drawing Sheets**(56)
